UNITED STATES PATENT OFFICE.

JOHN L. MOHUN, OF BROOKLYN, NEW YORK.

FLEXIBLE METALLIC CAR-ROOF.

1,069,564.

Specification of Letters Patent. Patented Aug. 5, 1913.

Application filed May 27, 1911. Serial No. 829,960.

To all whom it may concern:

Be it known that I, JOHN L. MOHUN, a citizen of the United States, residing at Brooklyn, in the county of Kings and State of New York, have invented new and useful Improvements in Flexible Metallic Car-Roofs, of which the following is a specification.

This invention relates to flexible car roofs of the same general character as that described in my two prior applications, Serial Nos. 587,803 and 587,804, both filed October 19, 1910, and in which hollow metal carlines, preferably of U shaped section, are employed for supporting metal roofing sheets, which drain into the troughs or channels in the carlines, and are covered at their edges by the carline caps.

One of the objects of my present invention is to provide an improved saddle connection at the ridge whereby the saddle projects over the ends of the carline caps and the ridge caps, and is supported directly upon the carlines a fixed distance above the roofing sheets, so that the weight of the running board is carried entirely by the carlines, and the carline caps, ridge caps and roofing sheets are securely held in place without clamping or pinching.

Another object is to provide a hood at the end of the carline rigidly secured thereto, and projecting over the end of the carline cap a fixed distance above the roof sheets whereby the end of the trough or channel in the carline is protected and the caps and roof sheets are securely held in place without pinching and without other means of fastening at these points.

Another object is to provide improved means for fastening the ridge pole and the purlins to the end plate of the car.

Another object is to provide a hood at the end of the ridge pole for protecting the end of the channel or gutter in the ridge pole and for securely holding the ridge cap in position.

Another object is to provide improved means for locking the ridge pole and purlins at the points of support upon the car lines.

Another object is to provide additional clearance at the eaves by moving down the facia board and securing the hoods and turned over edge of the roofing sheets directly to the side plate of the car above the facia board.

Another object is to provide improved means for supporting and protecting the boards of the running board extension whereby the weight is carried upon the car-line and the end plate of the car.

Another object is to provide an improved running board bracket for supporting the ends of said boards beyond the end of the car.

Another object is to provide improved means for fastening the roofing sheets at the corners of the car; and still another object is to provide improved means for supporting a lining beneath the metal roofing sheets.

A further object is to improve the construction of the edges of the roofing sheets beneath the carline caps so as to permit only a small amount of water or moisture being driven into the carline.

These and other objects will now be more fully described and the novel features will be set forth in the claims.

In the accompanying drawings: Figure 1 is a transverse section of a portion of a car roof embodying certain features of my improvement, the carline, hood, and saddle being shown in elevation; Fig. 2, a similar view taken near the end of the car, the carline being broken away, and showing the end plate of the car; Fig. 3, a transverse section on a larger scale, of a carline taken on the line 3-3 of Fig. 1, the top of the saddle being broken off; Fig. 4, a similar section taken on the line 4-4 of Fig. 1; Fig. 5, a transverse section of the ridge pole; Fig. 6, a longitudinal section of the ridge at the carline and showing one form of locking means for the ridge pole; Fig. 7, a similar sectional view of a purlin, taken at the point of support upon a carline, as indicated by line 7-7 of Fig. 1, and showing the means for locking the purlin by the web of the carline cap; Fig. 8, an end elevation of the ridge pole hood at the end of the car; Fig. 9, a section of a portion of the end of the car taken substantially on the line 9-9 of Fig. 8, the ridge hood being shown in elevation; Fig. 10, a section through the side plate of the car showing the end of the carline and carline hood in elevation, a portion of the side plate and hood being broken away; Fig. 11, an end elevation of the same; Fig. 12, a side elevation of the end of the car roof showing the running board extension; Fig. 13, a plan of the same; Fig. 14,

a plan of a portion of the roofing sheet at the corner of the car showing the means for binding the corner and locking the lag bolt; Fig. 15, a side elevation of the same; Fig. 16, a transverse section of a preferred modification of roofing sheets and carline cap construction at the carlines; Fig. 17, a section of a longitudinal roof member, either ridge pole or purlin, illustrating a preferred means of locking the same to the carline; Fig. 18, a side view of the same, the section of the carline being indicated in dotted lines; Fig. 19, an elevation of the running board bracket; Fig. 20, a section of the same taken on the line 20—20 of Fig. 19; Fig. 21, an enlarged detail view of a portion of a modified form of running board saddle having a wooden block to which the boards may be fastened by screws; Fig. 22, a transverse section of the same; Fig. 23, a section showing a modified form of carline for supporting a lining beneath the roofing sheets; and Fig. 24, a section of a purlin illustrating the means for fastening the same to the end plate of the car.

According to the construction shown in the drawings, the carlines 20 for supporting the roof are formed of metal, preferably pressed steel of U shaped section having a channel or trough for draining off water, and are supported at their ends upon the side plates 21 of the car which are cut out to form seats therefor so that the water from the channel in the carline may discharge over the side of the car. The longitudinal members, that is the ridge pole 25, and purlins 24, are also preferably formed of U shaped metal sections without flanges and are supported in depressed seats formed in the carlines for this purpose, as shown. If desired, openings may be formed in the bottom of the ridge pole and purlins at the points of support for the purpose of draining into the carlines.

The roofing sheets 23 are supported upon the carlines, ridge pole, and purlins, the two side edges of a sheet being arranged over the channels in the carlines and the top edge over the channel in the ridge pole, the side edges being covered by the carline caps 22 which rest freely upon the roofing sheets, while the upper edge is covered in a similar manner by the ridge cap 33.

According to my present improvement, all of the weight of the running board at the ridge is carried directly by the carlines, and for this purpose, I provide a running board saddle 40 having one or more projections 40^b extending down within the carline and fitting between the side walls thereof, to which it is rigidly secured by bolts 40^c. When bolted in position, the flange 40^a of the saddle is supported a fixed distance above the roofing sheets and extends over the upper ends of the carline caps 22, and

over the ends of the ridge cap sections which extend between the carlines and thereby holds in place said caps and the roofing sheets with sufficient pressure to make a reasonably tight joint and permit a sliding movement without clamping or pinching the roof sheets. This gives the desired flexibility to the roof to allow for expansion and contraction of the metal and the bending or weaving motion of the car.

The running board saddle is preferably formed of a malleable iron casting having a top flange with seats for the boards 41 which may be bolted thereto, as shown in Fig. 1, lugs being located upon the outside edges and between the edges of the boards. If preferred, the top flange may be dispensed with, and a wooden block 40^e, may be bolted to the saddle to which the running boards may be fastened by screws, as shown in Figs. 21 and 22.

For the purpose of locking the ridge pole against any longitudinal movement relative to the carlines, the saddle 40 may be provided with a depending flange 40^a, fitting into a notch cut in the ridge pole, as shown more particularly in Fig. 6. A similar lock for the purlin may also be made by having the depending web of the carline cap engage a notch in the purlin, as shown in Fig. 7. Another means for locking the longitudinal members, either ridge pole or purlin, to the carlines, is shown in Figs. 17 and 18, where a small casting 24^a, which extends out between the walls of the carline is riveted or otherwise attached or formed integral with the longitudinal member. As a means for securing the ends of the purlins, flanges 24^b, may be formed upon their ends which may then be bolted to the end plate of the car, as shown in Fig. 24.

The carline caps 22, preferably extend from the saddle near the ridge to a point near the eaves of the car, and for the purpose of holding the parts in place at the point, and also for protecting the end of the channel in the carline, I provide carline hoods 60. The ends of the carlines may have flanges 20^a, which flare over the side of the side plate, 21, and the hood 60 may be fastened directly to these flanges and to the side plate of the car, by bolts, 59, as indicated in Figs. 10 and 11. The hood extends over the lower end of the carline cap 22, holding the same in place, and the roofing sheet is preferably bent down over the end plate and over the flange at the end of the carline.

For the purpose of providing a clearance at the eaves of the car for the flared ends of the carlines and the hoods, the usual fascia board 58 is moved from its ordinary position flush with the top face of the side plate, to a lower position leaving sufficient space for the turned over edge of the roof

5 sheets, the carline flanges and hoods directly against the side of the side plate and above the fascia board 58, so that all of these parts may be within the outside line of the fascia 10 and be protected from being struck by objects along the track if they should happen to project far enough to reach the side fascia board of the car. The end of the roofing sheet 23 and the flange 20° of the carline sheet 23 and the flange 20° of the carline 15 may extend part way out over the top of the fascia board 58, as shown in Figs. 10 and 11, in order to insure the discharge of the water from the carline and roof out over the side of said board, and prevent moisture from dripping in behind the board.

16 Similar hoods 66 are provided for the ends of the ridge pole 25, which are cut through the end plates and have flanges 25°, on the outside to which the ridge hoods may be bolted, as shown particularly in Figs. 8 and 9. These hoods also have flanges which cover the ends of the ridge caps 33, and the roofing sheets, and securely hold the same in place at the same time protecting the end of the channel in the ridge pole from which water may discharge out over the end fascia board, as will be readily understood.

Another feature of my improvement relates to the running board extension from the ridge along the end to the side of the car, and comprises two angle bars 62, having the vertical flange cut away at the end where the bars are bolted or otherwise fastened to the underside of the running boards 41 and resting at the other end upon a longitudinal bar 42, which is supported at one end on a bracket 63, fastened to the end plate of the car and at the other end on a bracket portion of the carline hood 60 of the end carline, as shown particularly in Figs. 2, 12, and 13, of the drawing. This carline hood for the end carline is provided with an integral projecting portion, 60°, which carries one end of the bar, 42, 45 and extends down within and to the bottom of the carline in order to support the bracket a fixed distance above the roofing sheets. The boards, 43, of the running board extension are then supported on the angle bars, 62, and between the vertical flanges thereof which protect the ends of the boards and the entire weight thereof is carried by the end plate and carlines so that no weight is brought to bear upon the roofing sheets. This forms a simple, strong, 55 and durable construction and one entirely free from objections.

For supporting the running boards where the same project beyond the end of the car, 60 I provide an improved malleable iron bracket of the form shown in Figs. 12, 13, 19 and 20, and comprising two side bars adapted to be bolted to the end of the car, and a cross bar having seats for the ends 65 of the boards with an integral flange sub-

stantially flush with the top of the boards for protecting their ends and sides, and lugs 65 projecting between the edges of said boards. This forms a secure support to which the boards may be bolted, and protects the ends of the boards from injury.

A preferred form of roofing sheet and carline cap construction is shown in Fig. 16, in which the edges of the roofing sheets over the carlines are bent upward and over, forming a hook-shaped section, as indicated at 23°, beneath the carline cap 22, which may be formed of a shallow channel section inverted and adapted to rest upon the roofing sheet both at the carline flange and at the outer end of the hook-shaped portion, 23°. By means of this construction, an excessive amount of water will be prevented from draining into the carline even under severe storm conditions, since the greater portion of the rain which may be driven in under the carline cap will be deflected out again by the curved end of the roof sheet and the channel in the carline will not receive a greater amount of water than can be readily drained off through the discharge at its ends, thereby maintaining the interior of the car perfectly dry even in the severest storms.

Another feature of my improvement relates to the means for securing the roof sheets, 23, at the corners of the car, and consists in cutting the sheet diagonally inward at the corner for a short distance, then bending the same down over the corner and binding the corner with a short band, 23°, which may be riveted at 23° to the main sheet or fastened with lag screws 23° passing through both the binding strip and main sheet into the side or end plate of the car, as shown in Figs. 12, 13, 14 and 15 of the drawing. The band, 23°, may be bent out at its ends close to the heads of the lag screws, 23°, and thereby form a lock, 23°, to prevent the screws from turning. This serves to greatly stiffen the roof sheets at the corners and prevents the fastenings from becoming loose.

In Fig. 23 is shown a modified form of carline having the top flanges extended downward and outward at 20°, to form lower flanges for supporting for intermediate lining sheets 29, of wood or other heat insulating material, which may be located beneath the metal roof sheets, 23, but not necessarily in contact therewith. This serves to arrest or absorb much of the heat which may radiate through the metal roof, and keeps the interior of the car at a much lower temperature.

125 From the foregoing, it will now be apparent that by means of the various features of my improvement, a metallic car roof may be constructed which will be simple, light, flexible and durable, one which 130

provides a maximum overhead clearance within the car, and prevents the entrance of rain or moisture at all times, even under the most severe weather conditions.

Having now described my invention, what I claim as new and desire to secure by Letters Patent, is:

1. In a car roof, the combination of metal carlines having drain channels, roofing sheets supported thereon, caps for said carlines resting upon the roofing sheets, and saddles supported on the carlines a fixed distance above the roof sheets, and extending over the upper ends of the carline caps for holding down said caps and the roofing sheets.
2. In a car roof, the combination of metal carlines having drain channels and discharging over the side plates, roofing sheets having their side edges supported on said carlines over said channels, carline caps covering said channels and the edges of said roofing sheets, and metal hoods secured to the ends of the carlines over said drain channels and having discharge openings, said hoods also projecting over the ends of the carline caps for holding in place said caps and roofing sheets.
3. In a car roof, the combination of metal carlines, roofing sheets supported thereon, caps for said carlines resting upon the roofing sheets, a ridge pole and cap therefor, and running board saddles rigidly secured to the carlines a fixed distance above the roofing sheets, and provided with means for holding in place the ridge caps and the carline caps.
4. In a car roof, the combination of metal carlines, a metal ridge pole supported on the carlines and having a drain channel discharging at the end of the car, roofing sheets having their upper edges supported on said ridge pole over said channel, a ridge cap covering said channel and the upper ends of the roofing sheets, and a ridge hood secured at the end of the ridge pole over the channel discharge and having a flange extending over the end of the ridge cap for holding same in place.
5. In a car roof, the combination of metal carlines, metal roof sheets supported at their edges upon the carlines, carline caps covering the edges of the roof sheets, and running board saddles rigidly secured to the carlines for supporting the running board independently of the caps and roof sheets, and having flanges extending over the upper ends of the carline caps.
6. In a car roof, the combination of metal carlines, metal roof sheets supported at their edges upon the carlines, carline caps covering the edges of the roof sheets, a ridge pole supported on the carlines, a ridge cap formed in sections, and running board saddles rigidly secured to the carlines for supporting

the running board independently of the caps and roof sheets, and having flanges extending over the upper ends of the carline caps and the sections of the ridge cap.

7. In a car roof, the combination of metal carlines having drain channels, metal roof sheets supported at their edges upon the carlines, carline caps covering the edges of said roof sheets, and running board saddles having lugs extending down within the carlines and rigidly secured thereto, said saddles also having flanges at a fixed distance above the carlines and extending over the upper ends of the carline caps for holding the same in place.

8. In a car roof, the combination of metal carlines, a metal ridge pole carried thereby and having flanges at its end, and a hood covering the end of the ridge pole and fastened to said flanges.

9. In a car roof, the combination of metal carlines, a metal ridge pole carried thereby and having flanges at its end, roofing sheets supported on said carlines and ridge pole, a ridge cap covering the edges of the roofing sheets, a hood at the end of the ridge pole, and means for fastening the hood to the ridge pole flanges and to the end plate of the car.

10. In a car roof, the combination with metal carlines having flanges at their ends, caps for the carlines, and hoods located over the ends of the carlines and carline caps, and bolted to the carline flanges and the side plate of the car.

11. In a car roof, the combination with carlines and the side plate of the car, of metal roofing sheets bent over the outside edge of and fastened to the side plate above the facia board, and a facia board fastened to the side plate below the roofing sheets.

12. In a car roof, the combination with carlines and the side plate of the car, of a facia board secured to the side plate below the top thereof, and roofing sheets bent over the outside edge of the side plate and extended out upon the top edge of the facia board, said sheets being fastened to the side plates above the facia board.

13. In a car roof, the combination with metal carlines, and the side plate of the car, of a facia board secured to the side plate below the top thereof, roofing sheets and a carline hood fastened to the side plate above the facia board.

14. A running board extension for car roofs, comprising two angle bars bolted at the upper end to the running board, cross boards located between the upright flanges of the bars, and a cross bar supported on the end plate of the car at one end and on a carline at the other end for supporting the lower ends of the angle bars.

15. In a car roof, the combination with

U shaped metal carlines having depressions formed therein, of a longitudinal roof member supported in said depressions, and a laterally projecting piece of substantially the same width as the interior of the carline, rigidly attached to said member, and extending between the walls of the carline for locking the member in position.

16. In a car roof, the combination of U shaped metal carlines having their top flange extended downward and laterally to

form a lower flange, metal roofing sheets supported on the top flanges, and insulating lining sheets supported on the lower flange beneath the roofing sheets.

15

In testimony whereof I have hereunto set my hand.

JOHN L. MOHUN.
